UNITED STATES PATENT OFFICE

ERICH KÖNIGSBERGER, OF BRESLAU, GERMANY

HEADREST FOR TELEPHONES

Application filed July 10, 1931, Serial No. 549,895, and in Germany March 3, 1930.

This invention relates to a head rest for the telephone during use, consisting of bows to be placed on the head of the user, the holding devices proper being arranged on the ends of these bows. These head holders are designed to facilitate the transmission or receiving of long telephone messages, the user of the telephone having his hands free for writing down the messages.

10 The head rest for telephones according to the invention differs from the commonly used devices of known type in that the holding device proper consists of a box adapted to be closed in outward direction by a lid part, designed to be laid against the ear of the user and open in this direction, the internal dimensions of the box corresponding approximately to the dimensions of the earpiece of the telephone, the side wall of the 15 box being cut out in the front portion so that the cut out portion extending from the outer rim of the box corresponds to the thickness of the telephone handle. When the earpiece of the telephone has been placed into the box and when this box has been closed, the telephone is securely held in the correct position for talking and hearing. The telephone can be easily removed from the head rest and put back. As no screws or other fixing means 20 have to be operated to place the telephone into the head rest or to remove it from this head rest, these manipulations are facilitated and can be carried out very rapidly.

An embodiment of the invention is illustrated by way of example in the accompanying drawing in which:

Fig. 1 shows the head rest in perspective view.

Fig. 2 shows the head rest on a head in the 40 position of use.

The head rest for telephones consists of a bow 1 to be placed transversely on the head and of a bow 2 hingedly connected to the bow 1 and designed to be placed on the neck.

45 The transverse bow is composed of a middle part 1 and of two end parts 1', 1'' of thin resilient band steel shiftable under the middle part 1. The middle part 1 has two longitudinal slots 3 through each of which projects a knob 4 fixed on the corresponding end

part 1', 1'' respectively, so that by means of these knobs 4 the end parts can be shifted. The neck bow 2 consists of a covered spiral spring.

The end parts 1', 1'' of the head bow carry 55 each a holder for the earpiece 5 of the telephone having a handle 6 and a mouthpiece 7. The holder consists of a box shaped hollow cylinder having a bottom plate 9 with central aperture 8 and a side wall 10. In this side wall a portion 11 is cut out extending downwards from the outer edge. The holder is of such size that it can accommodate the earpiece 5 of the telephone, the handle 6 of the telephone being then located in the cut out portion 11, as shown in Fig. 1. The earpiece 5 of the telephone is then pressed against the ear by the action of the resilient bows 1 and 2, the mouthpiece 7 of the telephone being 60 in front of the mouth of the user. To securely hold the telephone in this position the holder proper may be closed by a cover. This cover consists of a strap 13 on the inner side of which a coiled spring 12 is fixed. The strap 13 is shown in Fig. 1 on the left side in the 65 lifted position and on the right side in the lowered or closing position. When the strap 13 is in the closing position the spring 12 is 70 put under tension and, exerting pressure upon the earpiece in the holder, secures the earpiece in the correct position. Any suitable fixing means such as a press button or the like may be provided for securing the strap 13 in the closing position.

The telephone can be placed in the right hand holder or in the left hand holder as desired.

The box shaped holders, and if possible other parts of the head rest, are made of leather to make the same as light as possible. The box shaped holders are preferably lined with soft material.

I claim:—

A head rest for a micro-telephone, comprising 85 in combination with an adjustable head band adapted to be placed over the head of the user, a hollow cylindrical box adapted to hold the ear piece of a micro-telephone consisting of a bottom plate with a central 90 aperture, a side wall having a cut out portion 100

to receive the handle of the micro-telephone
and a cover with a spring pressing the ear
piece tightly against the bottom plate of said
box and securely holding the handle in the
5 cut out portion of the side wall of said box
in the correct position for use, with the mouth
piece before the mouth of the user.

In testimony whereof I affix my signature.

ERICH KÖNIGSBERGER.
